UNITED STATES PATENT OFFICE

2,478,991

RAILWAY BRAKE BEAM

Glen J. Walker, Cleveland, Ohio, assignor to Chicago Railway Equipment Company, Chicago, Ill., a corporation of Illinois

Application November 20, 1947, Serial No. 787,201

15 Claims. (Cl. 188—223.1)

1

The invention relates to railway brake beams of the truss type in which compression and tension members converge near the ends of the beam and mount end members for carrying a brake shoe and for supporting the beam from the truck framing.

One object of the invention is to assure secure assembly of a brake head body part and a separately formed supporting part to each other and to the ends of a beam on which the parts are mounted.

Another object is to form the support engaging part of one metal or alloy and to form the brake head body part of another metal or alloy.

Another object is to cast one part about the other to form a rigid unit.

Another object is to provide a cast metal brake head body having a recess, arranged to receive the ends of the compression and tension members, with walls provided by a forged member so that machining of the cast head is unnecessary.

These and other detail objects, as will appear below, are attained by the structure illustrated in the accompanying drawings, in which:

Figure 1 is a plan view of a truss type brake beam embodying the invention, portions of the beam being cut away and the left-hand end of the beam being sectioned.

Figure 2 is in part an end view and in part a transverse vertical section taken approximately on the line 2—2 of Figure 3.

Figure 3 is a longitudinal vertical section through one end of the beam taken approximately on the line 3—3 of Figure 2.

Figures 4, 6 and 7 are views similar to Figure 3 and show other forms of the invention.

Figure 5 is in part an end view and in part a transverse vertical section taken approximately on the line 5—5 of Figure 6.

Figure 8 is a view similar to Figure 2 and shows the brake head of Figures 1 to 3 constructed symmetrically for interchangeable application to either end of the beam.

The beam shown in Figures 1 to 3 includes a compression member 1 of channel-shaped cross section, a tension member 2 of rectangular cross section, and a strut 3 intermediate the ends of the beam. The end portions of the compression and tension members converge, each end portion of the tension member being received between the compression member flanges 1a and engaging the inner face of the compression member web 1b. A lip 2a on the end of the tension member is seated against the ends of the compression member web and flanges. A brake head 4 is

5 mounted on each end of the beam. Brake head 4 includes a body 5 with forwardly projecting toes 6 for mounting a brake shoe 8 and a flat rectangular beam supporting part 10 extending outwardly of the beam and arranged to engage a support bracket (not shown) on an adjacent part of the truck framing. A recess 7 in the body receives the ends of the tension and compression members. The back wall 8 of the recess engages the outer face of the compression member web 1b and the top and bottom walls 9 of the recess engage the outer faces of compression member flanges 1a. The front wall 8a of the recess engages the forward face of the tension member and maintains lip 2a of the tension member in engagement with the end of compression member 1, thus increasing the strength of the beam and causing the tension and compression members to work together more nearly as a unit.

Part 10 has spaced legs 12 provided with laterally extending lugs 13. Legs 12 extend inwardly of the beam and within body 5. Part 10 preferably is made from a forging or bar and body 5 preferably is made of malleable iron or cast steel. Part 10 is placed in the mold and body 5 is cast around legs 12 with the metal of the body surrounding the legs and forming recess top and bottom walls 9. Lugs 13 interlock with adjacent portions of the body and secure part 10 and the body together. After the brake head is cast, it may be annealed to refine the grain in the casting and make it more malleable.

A horizontally disposed rivet 14 through the brake head and the ends of the tension and compression members maintains assembly of the beam. Rivet 14 passes through web 1b, of compression member 1, through tension member 2 and through back and front walls 8 and 8a of body 5 and between legs 12 of part 10.

40 Figure 4 shows a brake head 31 comprising a body 32 and a beam supporting part 33. Part 33 has legs 35 which extend within body 32 and form the top and bottom walls of a recess 36. By making part 32 from a forging or bar, it is unnecessary to machine the walls of recess 36. The ends of compression member 37 and tension member 38 are received in recess 36 and a horizontal rivet 39 extends through the compression member, through the tension member and through the brake head body and between legs 35 and maintains assembly of the beam. Brake head body 32 preferably is cast about the exterior only of legs 35 of supporting part 33, contacting the top face of the upper leg and the bottom face

of the lower leg, which faces are provided with lugs 40 to secure supporting part 33 to the body.

The brake head structure shown in Figures 5 and 6 is similar to that described in Figures 1-3 except that apertures 45 are provided in legs 46 of supporting part 47 instead of lugs, as shown in Figures 1-3. Brake head body 48 is cast about legs 46 and through apertures 45 and surround the legs.

In Figure 7, brake head body 51 is formed separately from supporting part 52. Part 52 has spaced legs 53 extending inwardly of the brake head and receiving between them the ends of the compression member 55 and tension member 54. A vertically disposed rivet 56 extends through body 51, through legs 53 of part 52, and through the ends of the tension and compression members. A horizontally disposed rivet 57 extends through body 51 and through the ends of the compression and tension members and between legs 53 of part 52. Rivets 56 and 57 maintain assembly of the beam. The ends of leg 53 of part 52 may be welded at W to the compression member instead of using vertical rivet 56 to secure part 52 to the beam members.

Figure 8 shows a brake head similar to that shown in Figures 1-3 except that the brake head is symmetrical about the axis y—y and may be applied interchangeably to either end of the beam. This is accomplished by positioning legs 61 of part 62 and recess 63 of body 64 symmetrically about axis y—y and with part 62 positioned parallel to the strut. The brake heads shown in Figures 4, 5, 6 and 7 show the parts at an angle to the strut so that the pull on the beam is parallel with the rail but these structures also may be made symmetrical about their central axes similarly to the brake head shown in Figure 8.

The details of the brake head and other parts of the beam may be varied otherwise than as described without departing from the spirit of the invention and the exclusive use of those modifications coming within the scope of the claims is contemplated.

What is claimed is:

1. In a railway brake head, a body part arranged to receive the ends of beam compression and tension members and arranged to mount a brake shoe, and a supporting part extending outwardly of said body part and arranged to engage an adjacent support bracket, one of said parts being preformed independently of the other part and said other part being cast on a portion of said preformed part.

2. In a brake head for a truss type railway brake beam, a body arranged to mount a wheel engaging device and having a pocket adapted to receive the adjacent ends of beam compression and tension members, and a part extending outwardly of said body and being arranged to engage an adjacent support bracket, said part being formed independently of said body and said body being cast about a portion of said part.

3. Brake head structure as described in claim 2 in which the part portion and body having integral elements interengaging each other to secure the part and body together.

4. In a brake head for a railway brake beam, a body arranged to mount a brake shoe and having a pocket adapted to receive the ends of beam compression and tension members, and a supporting part extending outwardly of said body and arranged to engage an adjacent support bracket, said part being formed of one material

and said body being of different material cast about said part.

5. In a railway brake head, a body arranged to receive the ends of beam compression and tension members and arranged for mounting a brake shoe, and a supporting part extending outwardly of said body and arranged to engage an adjacent support bracket, said part having spaced legs and said body being cast about said legs.

6. Structure as described in claim 5 in which the legs of the supporting part and adjacent portions of the body have respectively integral elements interlocking with each other to secure the body and part together.

7. In a railway brake head, a body arranged to receive the ends of beam compression and tension members and arranged for mounting a brake shoe, and a supporting part extending outwardly of said body and arranged to engage an adjacent support bracket, said part having spaced legs extending within said body, and said body being cast about said legs and surrounding each of said legs.

8. In a railway brake head, a body arranged to receive the ends of beam compression and tension members and arranged for mounting a brake shoe, and a supporting part extending outwardly of said body and arranged to engage an adjacent support bracket, said part having legs extending inwardly of the body and provided with transversely extending lugs, and said brake head being cast about said legs and interlocking with said lugs.

9. In a railway brake head, a body provided with a pocket for receiving the ends of beam compression and tension members and arranged for mounting a brake shoe, and a supporting part extending outwardly of said body and arranged to engage an adjacent bracket, said part having a leg, said body being cast about said leg and said leg forming at least one wall of said body pocket.

10. In a railway brake head, a body arranged to mount a brake shoe, and a supporting part extending outwardly from the body to engage a support bracket, said part having legs spaced to form opposite walls of a pocket for receiving the ends of beam compression and tension members, the body being cast about said legs and forming other walls of said pocket.

11. In a railway brake head, a body arranged to receive the ends of a beam compression and tension member and having means for mounting a brake shoe, and a supporting part at the end of the beam extending outwardly of said body and arranged to engage a support bracket on the truck frame, said part having legs provided with apertures, and said body being cast about said legs and into said apertures.

12. In a railway truss type brake beam, a channel shaped compression member and a tension member with their end portions converging, the end portions of said tension member being received between the flanges of said channel shaped compression member, elements on the tension member engaging the ends of the compression member, structure mounted on said end portions at each end of the beam for maintaining engagement of said members and including a brake shoe mounting body, a supporting part extending outwardly of said body and arranged to engage an adjacent support bracket, said part having legs spaced apart the depth of said channel member and receiving said channel member therebetween and extending within said body, and means main-

taining assembly of said structure to said members.

13. In a railway truss type brake beam, a compression member and a tension member with their end portions converging and interengaging and a brake head mounted on said end portions, said head comprising a body part arranged to mount a brake shoe and a supporting part extending outwardly of said body part and arranged to engage an adjacent support bracket, one of said parts being pre-formed independently of the other part and said other part being cast about a portion of said pre-formed part, and a securing device maintaining assembly of at least one of said parts to at least one of said members.

14. In a railway truss type brake beam, a compression member and a tension member with their end portions converging, elements on the tension member engaging the ends of the compression member, structure mounted on said end portions at each end of the beam for maintaining engagement of said tension member element with said compression member and including a brake shoe mounting body and a supporting part extending outwardly of said body and arranged to engage an adjacent support bracket, said part having spaced legs extending within said body and receiving between them and engaging said end portions, and means maintaining said structure assembled with said members.

15. In a railway truss type brake beam, a compression member and a tension member with their end portions converging, elements on the tension member engaging the ends of the compression member, structure mounted on said end portions at each end of the beam for maintaining engagement of said tension member element with said compression member and including a brake shoe mounting body and a supporting part extending outwardly of said body and arranged to engage an adjacent support bracket, said part having spaced legs extending within said body and receiving between them said end portions, and a vertically disposed rivet extending through said body, legs and members and a horizontally disposed rivet extending through said body and said members and between said legs for maintaining assembly of said structure to said members.
